(57) **CLAIM**

The ornamental design for a coffee press cylinder as shown and described.

DESCRIPTION

The file of this patent contains at least one photograph executed in color. Copies of this patent with color photographs will be provided by the Office upon request and payment of the necessary fee.

FIG. 1 is a side view of a coffee press cylinder showing our new design;

FIG. 2 is another side image thereof;

FIG. 3 is another side image thereof;

FIG. 4 is another side image thereof;

FIG. 5 is another side image thereof;

FIG. 6 is another side image thereof;

FIG. 7 is another side image thereof;

FIG. 8 is another side image thereof;

FIG. 9 is a top side image thereof;

FIG. 10 is a bottom side image thereof;

FIG. 11 is a perspective view image thereof; and,

FIG. 12 is a perspective view image thereof.

The AeroPress logo shown in the photographs forms no part of the claimed design.
